UNITED STATES PATENT OFFICE.

RICHARD HEARD, OF BOSTON, MASSACHUSETTS.

DESIGN FOR A RULER.

SPECIFICATION forming part of Design No. 34,776, dated July 16, 1901.

Application filed May 24, 1901. Serial No. 61,814. Term of patent 3½ years.

To all whom it may concern:

Be it known that I, RICHARD HEARD, a citizen of the United States, residing at Boston, in the county of Suffolk and State of Massachusetts, have invented and produced a certain new and original Design for Rulers, of which the following is a specification, reference being had therein to the accompanying drawings.

10 Figure 1 is a top plan view, and Fig. 2 is a side elevation, of a ruler, showing my new design.

As shown in the drawings, the leading or material feature of my design consists of the 15 surface ornamentation of the ruler, this ornamentation comprising the two opposite parallelograms 1 1, each containing the oppositely curved and crossed lines 2 and 3. Between the marginal parallelograms 1 1, which 20 extend from end to end of the straight sides of the ruler, there is a relatively broader surface 4 of the same length as the marginal parallelograms 1 1, this relatively broader surface 4 being ornamented with conventionalized leaves 5, extending lengthwise of the 25 surface 4, with conventionalized curved branches 6 at the sides of and between the leaves 5 and

with small circles 7 grouped near the leaves 5 and branches 6 at intervals along the parallelograms 1 1, but inwardly therefrom toward said leaves and branches.

The opposite straight sides of the ruler terminate at each end in straight shoulders 8 8 8 8, there being two shoulders near each end portion of the ruler and each shoulder being at 35 right angles to the lengthwise axis of the ruler. From between each pair of shoulders at the same end of the ruler a lobe 9 projects. The lobes 9 are semicircular in outline, viewed in plan, while their surfaces 4^a are ornamented 40 with radially-disposed conventionalized petals 10, the inner ends of which are grouped at the leaves 5 on the surface 4, which is continuous with the surfaces 4^a 4^a.

What I claim is—

45 The design for a ruler, as herein shown and described.

In testimony whereof I affix my signature in presence of two witnesses.

RICHARD HEARD.
